UNITED STATES PATENT OFFICE.

EMMETT W. STULL, OF NORWOOD, OHIO, ASSIGNOR TO THE BULLOCK ELECTRIC MANUFACTURING COMPANY, A CORPORATION OF OHIO.

CONTROLLER.

No. 869,812.

Specification of Letters Patent.

Patented Oct. 29, 1907.

Application filed August 17, 1904. Serial No. 221,027.

To all whom it may concern:

Be it known that I, EMMETT W. STULL, a citizen of the United States, residing at Norwood, in the county of Hamilton and State of Ohio, have invented certain 5 new and useful Improvements in Controllers, of which the following is a full, clear, and exact specification.

My present invention relates to improvements in systems of motor control, and more particularly to motor controllers of the type usually employed on electrically 10 propelled vehicles.

The main object of my invention is to so organize a system of control for a plurality of motors as to obtain a uniform acceleration of the motors through series and parallel connections and a further object is to improve 15 the structural parts of the motor controller so as to reduce its cost of manufacture and increase its efficiency.

The invention therefore consists, in one of its aspects, of the combination of a pair of motors, with means, such 20 as a motor controller of the cylindrical type, for connecting said motors first in series, then short-circuiting part of the field of each motor to increase the speed, then connecting each motor in series with part of the field of the other motor leaving the armature and retaining 25 field of one motor in parallel to the armature and remaining field of the other motor, then connecting the motors in parallel.

The invention in another of its aspects comprises a controlling cylinder, a star-wheel mounted to rotate 30 with said cylinder, and a spring-pressed pawl engaging said star-wheel, the periphery of said star-wheel being so formed as to offer greater resistance to the spring pressed pawl while passing from notch to notch during the forward movement of the controller cylinder than 35 during the backward movement of said cylinder to obtain an improved snap action between positions during forward movement.

The invention further comprises an interlock between the operating cylinder and the reversing switch 40 of the controller, which includes a cylindrical apron carried by the controller shaft and formed with an opening through which the end of a pivoted lever is adapted to pass provided the cylinder is in its "off" position, said lever being spring-pressed against a cam, which is 45 constructed and arranged to force said lever end into said opening while the reversing switch is being moved from either of its operative positions to "mid" position or vice versa, but it will not hold the lever in said opening when the reversing switch is in its "mid" position. If the controlling cylinder is in any position 50 other than its "off" position when the reversing switch is attempted to be moved from one position to another, the lever will strike said apron and prevent such movement.

In another of its aspects my invention comprises a blow-out magnet, having its core attached to or formed integral with the casing of the controller and one of its pole pieces formed of a sheet of magnetic material, held in place on the core by means of positioning pins and a single bolt, the said plate preferably carrying a plurality of strips of insulating material, which, when the plate is in position on the core, fit between the fingers of the controller to form arc deflectors.

The invention also includes an improved arc deflector formed of strips of insulating material mounted on rods passing therethrough, said strips being separated from each other the required distance by sleeves of insulating material mounted on said rods, which are held in position on their support by means of readily removable blocks through which the supporting rods pass.

The invention also comprises in a series-parallel controller a single rotatable cut-out switch, which is adapted to cut out one or more motors controlled by said controller, leaving the remaining motor or motors connected in circuit, so as to be controlled rheostatically. An interlock may also be provided for preventing the operating cylinder from moving past a predetermined position when my improved cut-out switch is moved into a position to cut-out of circuit one or more of said motors.

In the accompanying drawings Figure 1 illustrates a front elevation of my improved controller with the casting cover removed, the cap plate being shown in section; Fig. 2 is a diagrammatic representation of my improved system of motor control with the controller shown in development as is customary in illustrating such structures; Fig. 3 is a top plan view of the controller cap plate; Fig. 4 is a sectional plan view of the controller on the line 4—4 of Fig. 1; Fig. 5 is a sectional plan view of the controller on the line 5—5 of Fig. 1; Fig. 6 is a side view of the lower part of the controller, showing the face view of my improved cut-out switch; Fig. 7 is a detail sectional view on the line 7—7 of Fig. 1, illustrating the operating mechanism for the interlock between the cut-out switch and the controlling cylinder; Fig. 8 is a sectional plan view in detail of the mechanism shown in Fig. 7, the view being taken on the line 8—8 of Fig. 1; Fig. 9 is a front elevation of the blow-out magnet pole piece with the arc deflectors mounted thereon; Fig. 10 is a plan view of the device shown in Fig. 9; Fig. 11 is a section on the line 11—11 of Fig. 9; Fig. 12 is a section on the line 12—12 of Fig. 9, and Fig. 13 represents diagrammatically the different circuit combinations and connections made by the motor controller in its successive operative positions.

Referring to Fig. 1 the main controller cylinder is illustrated at 15. This cylinder has the customary contact segments 16, which are mounted on sleeves of con-

ducting material; said sleeves being insulated from the shaft 17, by a layer of insulating material. The relatively fixed contact fingers which engage said segments are indicated at 18. These contact fingers are preferably made adjustable by means of adjusting screws 19, which will be hereinafter described. Mounted on the upper end of the shaft 17 is an operating handle 18^a, which has a hooked lug 19^a on its under side, engaging with the customary notched flange 20 formed on the cap plate 21. The flange and the hooked lug are so arranged that the handle can only be placed in position on the shaft 17 when the controller is at its "off" position; the hooked lug 19^a then passing readily through the notch 22. The reversing switch 23 also has its shaft 24 extending through the cap plate 21, and on its irregularly shaped upper end is placed an operating handle 25, said handle being provided with a hooked lug 26 engaging the notched flange 27. The operating handle of the reversing switch can only be removed when the latter is in its "mid" or "off" position. The handle 25 is so shaped, being bent upwardly at 28, that it can not be placed in position on the shaft 24 in a reversed position. The motorman is thus prevented from operating the reversing switch in any other than the proper manner, thereby reducing the danger of the reversing switch being left in either of its operative positions when the motorman leaves the car.

As clearly shown in Figs. 1 and 4, the upper ends of the shafts 17 and 24 operate in bearings 30 and 31 respectively, which are bolted to the back of the controller casing at 32 and 33 respectively. Thus it is easy to remove the cap plate of the controller by simply removing the operating handles and the screws 34 without deranging the relative positions of the operating cylinder and reversing switch. The lower end of the controller cylinder shaft 17 operates in the step bearing 35, while the lower end of the shaft 24 of the reversing switch is supported in the bearing 36. The reversing switch is provided with the customary contact segments, with which the contact fingers *g* and *h* engage. The arrangement of these contact fingers on opposite sides of the reversing switch cylinder is clearly shown in Fig. 5.

The interlock between the reversing switch cylinder and the operating switch cylinder of the controller will now be described. Referring particularly to Figs. 1 and 4, it will be seen that the reversing switch cylinder is provided with a notched cam 41, the notches 42 therein corresponding to the operative positions of the reversing switch and the notch 43 corresponding to the "off" or "mid" position of the said reversing switch. The lever 44 pivoted at 45 is normally held against said cam by means of the spring 46. Said lever 44 is provided with a projection 47, which is adapted to enter the opening 48 in the cylindrical apron 49 carried by the operating cylinder shaft, only when the controlling cylinder is at its "off" position. In any other position of the controlling cylinder, when an attempt is made to move the reversing switch from one position to another, the projection 47 will strike the apron 49 and prevent any movement of the reversing switch. The notch corresponding to the "mid" position of the reversing switch is so shaped that the projection 47 does not enter the opening 48 when the reversing switch is in said position. Therefore when the reversing switch

cylinder is in its "mid" position, the main operating cylinder is not locked against movement. It is only locked against movement while the position of the reversing switch is being changed, and the main cylinder must be in its "off" position before a movement of the reversing switch can take place. As shown the apron 49 is preferably formed integral with star-wheel 50. The star-wheel 50 has the notches on its periphery so shaped that during the forward movement of the controller; that is, the movement of the controller cylinder in a clock-wise direction (Fig. 4) the pivoted spring-pressed pawl 51 is retarded much more in its action than during a backward movement of the controller. This is accomplished by giving the side 52 of each of the projections on the periphery of said star-wheel a sharper angle than the side 53 of said projections. It will be seen that during the forward movement of the controller the antifriction wheel 54 on the spring pressed lever 51, has to climb a sharper angle than during the backward movement in order to pass the projections of said wheel. This gives a desirable snap action between the operative positions of the controller and tends to prevent a too rapid forward movement of the cylinder.

The contact fingers of the controller are mounted on an insulating block 55 shown clearly in Fig. 5 and each finger consists of the spring strip 56, having a heavy contact mounted at its outer end, and fastened to the terminal 57 at its inner end by means of the bolt 58, said strip having its tension adjusted by means of the adjusting screw 19 passing through the bracket 59, which is also fastened in position by means of the bolt 58.

The blow-out magnet core is indicated at 60, said core being preferably formed integral with the back of the controller casing. The coil of said magnet is indicated at 61. The front pole-piece of the blow-out magnet is formed of a single flat plate of magnetic material of the shape indicated in Fig. 1 by broken lines, and in Fig. 9 by full lines. The said pole piece is held on the core 60, by means of the bolt 65, which passes through the opening 66 of the plate (Fig. 9), and is held firmly against movement about the bolt 65, by means of the positioning pins 63 and 64, which pass through the opening 67 and 68 formed in said plate (Fig. 9). It will thus be seen that the plate is readily removable by simply unscrewing a single bolt. The said plate 62 has one side almost completely covered by insulating material 70, and mounted upon said strip on the side carrying said insulating material are the holding blocks 71 and 72 held in position by means of the screws 73. Through vertical openings in said blocks pass the supporting rods 74, upon which are mounted alternately strips of insulating material 75, and sleeves of insulating material 76. The sleeves of insulating material are cut to the lengths desired to separate the strips 75 of insulating material forming the arc deflectors to the required distance. An outer rod 77 passes through openings formed in the arc deflector strips and has mounted thereon sleeves of insulating material 76, similarly to rods 74. The strip of insulating material 78 to which each one of the insulating arc deflector strips is fastened is preferably employed to give the structure greater rigidity. The material mounted on each of the vertical supporting rods is held tightly in position by means of the clamp-

ing nuts 80. This structure provides a very light, effective, cheap, while at the same time very efficient arc deflector.

The single rotatable cut-out switch for the motor is located in the lower part of the controller casing and has its operating shaft 85 extending through the side of said casing at 86. As shown in Fig. 6 the outer end of the shaft 85 is provided with a collar 87, carrying an index finger 88, which points to one of the three operative positions of the cut-out switch indicated at 89, 90 and 91. Directly opposite these indicating projections is a notched flange 92, provided with notches corresponding to the different positions of the cut-out switch. The cut-out switch has its shaft end formed irregular, similar to the end of the reversing switch shaft, and is operated by the reversing switch handle 25, the hooked lug extension of said handle passing through the notches in the notched flange 92 in the different operative positions of said switch. This construction prevents the handle from being removed from the end of the shaft 85 when the cut-out switch is in any of its intermediate positions. Mounted upon the shaft 85 (Fig. 1), are collars of insulating material 93 and 94 between which are mounted the contact sectors 95, 96, and 97, shown clearly in dotted lines in Fig. 6. These contact sectors are adapted to be embraced by the relatively fixed spring contact fingers 98, 99, 100, 101, and 102, which are mounted within the protecting box 103 and are connected in the motor circuit in a manner to be herein-after described. As the shaft 85 is rotated, the contact sectors are moved into and out of engagement with the spring contact fingers to cut out or cut in one or the other motor or pairs of motors.

A mechanical interlock between the cut-out switch and the operating cylinder is preferably provided. The inner end of shaft 85 carries a collar 104 provided with a cam surface which engages the spring pressed bell crank lever 106, pivoted about the vertical axis 107 and forced into engagement with said cam surface by means of the spring 108. The arm 109 of the bell crank lever is normally maintained in the back part of the controller casing in the position shown in Fig. 8, but when the shaft 85 is rotated the cam 105 causes the bell crank lever to move about its vertical axis and 45 throw the arm 109 into the path of the lug 110 carried by the collar 11, pinned to the lower end of the shaft 17. In the series-parallel controller shown this lug 110 occupies a position corresponding to the final series position, or final rheostatic control position, of the 50 motor controller cylinder. It will thus be seen that when the cut-out switch is operated to cut out one or more of the motors, the remaining motor or motors may be operated rheostatically but the controller cylinder is prevented by the locking arm 109 from moving 55 past the final series position, thereby avoiding the possibility of cutting the remaining motor out of circuit by moving the controller cylinder into the parallel positions. By using such a simple construction of cut-out switch and interlock, I am enabled to economize 60 space in the controller, to cheapen the cost of production, to avoid the necessity for using a plurality of cut-out switches, and also render it impossible to operate the cut-out switch unless the motor circuit is opened at the reversing switch.

65 Referring now to Fig. 2, M, M¹, M², and M³ represent

the motors of a four motor equipment, controlled according to my improved method of control. The armatures of said motors are represented by a, a¹, a², and a³. The field coils of said motors are each divided into two parts, the fields of motor M being indicated by f and f^a, 70 of M¹ by f¹ and f^{1a}, M² by f² and f^{2a}, and M³ by f³ and f^{3a}. In this diagram the motor controller, the reversing switch and the cut-out switch are shown in customary development. The controller contact fingers are represented by c¹ to c¹⁶ inclusive. The contact segments 75 on the controller cylinder are represented by d¹ to d¹⁶ inclusive, e², e⁷, e⁹, e¹⁰, and e¹⁰. One row of contact fingers on the reversing switch includes fingers g¹ to g⁷ inclusive. The other row of contact fingers is indicated by h¹ to h⁷ inclusive. The contact segments on one side 80 of the reversing switch are indicated by k¹ to k⁵ inclusive, m¹, m², and m³, and on the other side by n¹ to n⁵ inclusive, and p¹, p², and p³. The coil of the blow-out magnet is indicated as before at 61. The contacts of the cut-out switch are shown at 98, 99, 100, 101, and 102, 85 while the contact sectors which engage said contacts are indicated at 95, 96, and 97. The resistance connected in the circuit with the motors during the series operation and during the rheostatic operation of a single motor or pair of motors is indicated at R. 90

In the operation of my improved system of motor control, as the motor controller is moved into its first operative position, indicated by the vertical dotted lines 1—1, a circuit is completed through the motors as follows. From the trolley T through the blow-out 95 magnet coil 61, contact finger c¹⁶ of the motor controller, contact segments d¹⁶ and d¹⁵, contact finger c¹⁵, resistance R, contact c⁸, contact segments d⁸ and d¹⁰, contact finger c¹⁰, contacts 101, 97, and 102 of the cut-out switch, contact finger g⁴ of the reversing switch; then supposing the reversing switch is thrown to the right, through contact segment k³, where the circuit divides, one branch circuit being traced through the contact segment k¹, contact finger g¹, field f, and f^a of the motor M, contact finger g³ of the reversing switch, contact segment k², contact finger g², armature a of motor M, through the contacts 99, 96, and 100 of the cut-out switch, contact finger c⁶ of the motor controller, contact segments d⁶ and d⁷, contact finger c⁷ to the point 105 120 where the circuit again divides, one branch being traced through the armature a² of the motor M², contact finger h² of the reversing switch, contact segment n², contact finger h³, field coils f^{2a} and f², of the motor M², contact finger h¹ of the reversing switch, contact segments n¹ and n³, contact finger h⁴, to ground at G. 110 The circuit also branches from the contact segment k³ in the reversing switch through the contact segment k⁵, contact finger g⁷, field coil f^{1a} and f¹ of the motor M¹, contact finger g⁵ of the reversing switch, contact segment k⁴, contact finger g⁶, armature a¹ of the motor M¹ 115 to the point 121, from which the circuit is completed as before described. A branch circuit is also completed from the point 120 through the armature a³ of the motor M³, contact finger h⁶, contact segment n⁴, contact finger h⁵, field coils f³ and f^{3a} of the motor M³, 120 contact finger h⁷, contact segment n⁵ through the segment n³, and finger h⁴ from which the circuit is completed to ground at G as before described. It will be seen that the motors M and M¹ are connected in parallel with each other in series with the motors M² 125 and M³. 130

and M^3 , which are also connected in parallel with each other. The connections corresponding to this position of the motor controller are clearly shown in Fig. 13.

As the motor controller cylinder is moved forward 5 through the second, third, and fourth positions, the sections of the resistance R are successively cut out until the motor controller is in the fifth position, indicated by the vertical dotted line 5—5. The motors are thus connected in series in the manner indicated by the fifth 10 position, Fig. 13, the resistance R being entirely cut out of the circuit. In this position of the controller the circuit from the contact finger c^{10} is completed through contact finger c^{10} , through the contact segments d^{10} , d^{11} , d^{11} , f^{10} , and e^{10} . As the controller cylinder is moved 15 into its next operative position, the contact segments d^2 and d^3 are brought into engagement with the contact fingers c^2 and c^3 , and a shunt circuit is thereby thrown around a part of each of the fields of the motors as indicated in the sixth position, Fig. 13. This shunt connection 20 weakens the fields of each of the motors and thereby increases their speed.

In passing from the sixth position into the seventh position, in which, as shown in the seventh position, Fig. 13 the armatures and part of the fields of one pair 25 of motors are connected in series with the remaining part of the fields of the other pair of motors, the controller passes through several transitional positions indicated at 6^a, 6^b, and 6^c, Fig. 13, in which the motors are connected successively in series as shown in 6^c, 30 corresponding to the fifth position of the controller; then in position 6^b a shunt is thrown around the armatures and part of the fields of one pair of motors, leaving the remaining pair, such as M and M^1 , connected in series with the remaining part of the fields of the motors M^2 and M^3 , then in position 6^c, the series connection 35 is broken at the point 122, corresponding to the contact fingers c^6 and c^7 and contact segments d^6 and d^7 , Fig. 2, then the armatures and remaining part of the fields of the motors M^2 and M^3 are connected in series 40 with parts of the fields of the motors M and M^1 by throwing a shunt around the armatures and parts of the fields of the motors M and M^1 . This last step is accomplished by the engagement of the contact segments e^7 and e^8 with the contact fingers c^7 and c^8 in Fig. 2. The controller 45 is now in its seventh operative position, which if desired, may be used as a running position, it being understood that the transitional position between the sixth and seventh positions are not running positions and should be passed over very rapidly. In passing 50 from the seventh position to the eighth position of the controller, the series connection between the motors is first broken at the point 123, corresponding to the multiple break between the contact fingers c^7 , c^8 , c^4 , and c^5 and the contact segments c^2 , d^3 , d^1 , and d^5 of the 55 motor controller in Fig. 2. This leaves the motors M^2 and M^3 connected in series with the field coils f^1 and f^3 of the motors M and M^1 , the armature and field coils f^6 and f^{1a} of said motors being cut out. This position is indicated at 7^d Fig. 13. The motors M^2 and M^3 are then 60 thrown directly across the line in parallel. This is accomplished by a shunt around the field sections f^1 and f^3 of the motors M and M^1 , and the connections are indicated at 7^e Fig. 13. The next transitional position indicated by 7^f disconnects the armatures and fields 65 of motors M and M^1 entirely from the circuit, prepara-

tory to making the connections indicated in the eighth position, in which the pairs of motors are connected in parallel across the line; that is to say, the position in which all of the motors are connected directly across the line, each armature being in series with the entire field of its motor. An increase in speed of the motors is obtained in passing from the sixth to the seventh position, since the armatures and parts of the fields of each of the motors are connected in parallel, each pair being connected in series with the part of the field coils of the other pair of motors, thereby supplying additional current through that remaining section of the fields, which increases the magnetic field strength of each motor to hold the speed down below that obtained when the motors are all in parallel, but permits a higher speed 70 than that obtained when the motors are connected in series. The circuits corresponding to the final or eighth position of the motor controller will now be traced on Fig. 2. Starting with the trolley T through the blow-out coil 61, contact finger 16, contact segment 75 d^{10} , contact segment d^{11} , contact fingers e^{11} , and c^7 to point 120, from which the circuit may be traced through the armatures a^2 and a^3 and fields f^2 , f^{2a} , f^3 and f^{3a} of the motors M^2 and M^3 , connected in parallel to the contact finger k^1 , from which a circuit is completed to 80 ground at G . From the contact segment d^{11} , a branch circuit is also completed through the contact segments f^{10} , contact finger c^{10} , contacts 101, 97, and 102 of the cut-out switch to the contact finger g^1 of the reversing switch, from which the circuit may be traced through 85 the contact segments k^2 , k^4 , and k^5 , fields f^1 , f^3 , f^1 , and f^{1a} , and armatures a and a^1 of the motors M and M^1 in parallel to the point 121. Hence through the contacts 99, 96, and 100 of the cut-out switch to the contact finger c^6 , hence through the contact fingers c^5 and c^1 to the 90 contact segment d^1 to ground, preferably in the controller casing at G^1 .

While I have shown my invention as embodying a specific type of motor controller and a system of control for a four motor equipment, I do not care to be so limited, as many changes and modifications may be made in the controller and number of motors controlled without departing from the spirit or scope of the invention, and I aim in the appended claims to cover all such changes or modifications.

Having thus described my invention, what I desire to claim and secure by Letters Patent is:—

1. In a system of motor control, a pair of motors and a motor controller constructed and arranged to connect the motors first in series, then short circuit part of the field of each motor, then connect each motor in series with part of the field of the other motor so that the armature and remaining field of one motor will be in parallel to the armature and remaining field of the other motor, then connect the motors in parallel.

2. In a system of motor control, the combination with a pair of motors, of a motor controller constructed and arranged to connect the motors in series and parallel relationship by first connecting them in series, then short-circuiting the armature and part of the field of one motor, then connecting each motor in series with part of the field of the other motor with the motor armatures and remaining fields in parallel, then connecting the motors in parallel.

3. In combination, a pair of motors, and a motor controller constructed and arranged to connect the motors in series and parallel by first connecting them in series, then connecting each motor in series with part of the field of the other motor while severing the series connection be-

- between the motors, then cutting out the armature and part of the field of one motor, then short-circuiting the remaining field of the last mentioned motor, leaving the other motor connected directly across the line, then connecting the motors in parallel. 5 for cutting out of circuit one or more of said motors and for connecting the remaining motor or motors in circuit so as to be controlled by said controller rheostatically only. 75
4. In a controller, an operating cylinder, a reversing switch, and an interlock between the operating cylinder and the reversing switch comprising a cylindrical apron carried by the controller shaft and provided with an opening in its side, a pivoted lever arm, an end of which is adapted to enter said opening, a cam carried by the reversing switch against which said arm is yieldingly pressed, said cam being constructed to force said lever end into said opening as the reversing switch is moved from one position 10 to another, but to permit said lever to withdraw from said opening when the reversing switch is in its "off" or inoperative position.
5. In a controller, an operating cylinder, a star wheel mounted to rotate with said cylinder, and a spring pressed 20 pawl engaging said star wheel, the periphery of said star wheel being so formed as to offer greater resistance to the spring pressed pawl while passing from notch to notch during the forward movement of the operating cylinder than during the backward movement thereof to obtain an 25 improved snap action between operative positions during forward movement of the cylinder.
6. In a controller, a blow-out magnet having one of its pole-pieces formed of a sheet of magnetic material, a plurality of strips of insulating material mounted on said pole 30 piece to act as arc deflectors, and means for holding said pole piece on the magnet core consisting of positioning pins and a single bolt.
7. In a motor controller, a casing, a blow-out magnet having its core formed integral therewith, a removable pole 35 piece attached to said core, and means for holding said pole piece in position comprising a plurality of positioning pins and a single bolt.
8. In a controller, a blow-out magnet, a pole piece therefor, and means for fastening said pole piece to the core of 40 said magnet comprising positioning pins and a bolt, the whole being so arranged that the pole piece will be held in a definite position on the core, but may be readily removed therefrom by the removal of a single bolt.
9. In a controller, a blow-out magnet, a plate of magnetic material forming one of the pole pieces for said magnet, 45 are deflectors carried by said plate formed of strips of insulating material mounted on rods passing therethrough and separated from each other the proper distance by sleeves of insulating material mounted on said rods, and 50 means for fastening said rods to said plate.
10. In a controller, an arc deflector formed of strips of insulating material, rods upon which said strips are mounted, sleeves of insulating material on said rods acting as separating pieces for said strips, a supporting plate, 55 and means for fastening said rods to said plate.
11. In a controller, a magnet pole piece, and an arc deflector carried by said pole piece formed of strips of insulating material mounted on rods passing therethrough, said strips being separated from each other the required 60 distance by sleeves of insulating material mounted on said rods, the latter being held in position on said pole piece by readily removable blocks through which said supporting rods pass.
12. In a series parallel controller, a single rotatable cut- 65 out switch adapted to cut out of circuit one or more of the motors controlled by the controller and connect the remaining motor or motors in circuit so as to be controlled rheostatically and means for controlling the motors rheostatically.
- 70 13. In combination, a plurality of motors, a controller for controlling said motors rheostatically and in series and parallel combinations, a single rotatable cut-out switch
- for cutting out of circuit one or more of said motors and for connecting the remaining motor or motors in circuit so as to be controlled by said controller rheostatically only. 75
14. In combination, a pair of motors, a series-parallel controller therefor, and a rotatable cut-out switch which when in a certain position cuts one motor out of circuit and connects the remaining motor in circuit to be controlled rheostatically by said controller, and when in another position cuts out the second motor and connects the first to be controlled rheostatically. 80
15. In combination, a pair of motors, a series parallel controller therefor, and a rotatable cut-out switch which when in a certain position cuts one motor out of circuit and connects the remaining motor in circuit to be controlled rheostatically by said controller, and when in another position cuts out the second motor and connects the first to be controlled rheostatically, and a mechanical interlock between said series parallel controller and said cut-out switch operating to prevent the controller from moving past its series positions when the cut-out switch is in either of said cut-out positions. 85
16. In combination, a plurality of motors, a controller for controlling said motors rheostatically and in series and parallel combinations, a single rotatable cut-out switch for cutting out of circuit one or more of said motors and connecting the remaining motor or motors in circuit so as to be controlled rheostatically only, and a mechanical interlock for preventing the controller moving beyond a predetermined position when the cut out switch is moved to cut out any motor. 90
17. In a motor controller, a reversing switch, the shaft of which has an irregularly shaped end, a handle adapted to fit said shaft end, a hooked lug on said handle, a notched flange with which said lug is adapted to coact, a cut-out switch having its shaft end shaped similarly to the reversing switch shaft end and provided with a similar notched flange, the whole being so constructed and arranged that when the reversing switch is in its "off" position, the handle may be removed therefrom and employed to operate the cut-out switch. 105
18. In combination, a pair of motors, and means for connecting said motors in series and parallel relationship which includes means for accomplishing the intermediate step of connecting each motor in series with a field winding and not with the armature of the other motor. 110
19. In a system of motor control, a pair of motors and a motor controller constructed and arranged to connect the motors first in series, then connect each motor in series with but part of the field and not the armature of the other motor, and then connect the motors in parallel. 115
20. In a controller, an operating cylinder, a reversing switch, and an interlock between the operating cylinder and the reversing switch so constructed and arranged as to prevent movement of the operating cylinder as the reversing switch is moved from one position to another but to permit such movement when the reversing switch is in its "off" or inoperative position. 120
21. In a controller, an operating cylinder, a reversing switch, and an interlock between the two, said interlock being constructed and arranged to prevent movement of the reversing switch save when the operating cylinder is in "off" position, and to permit movement of the operating cylinder when the reversing switch is in either its "ahead," "back" or "off" position while preventing such movement when the reversing switch is not in one of such positions. 125
- In testimony whereof I affix my signature, in the presence of two witnesses.
- EMMETT W. STULL.
- Witnesses:
- FRED J. KINSEY,
GEORGE W. CAPPIN.

It is hereby certified that in Letters Patent No. 869,812, granted October 29, 1907, upon the application of Emmett W. Stull, of Norwood, Ohio, for an improvement in "Controllers," an error appears in the printed specification requiring correction, as follows: In line 46, page 3, the reference numeral "11" should read *111*; and that the said Letters Patent should be read with this correction therein that the same may conform to the record of the case in the Patent Office.

Signed and sealed this 12th day of November, A. D., 1907.

[SEAL.]

C. C. BILLINGS,

Acting Commissioner of Patents.
